UNITED STATES PATENT OFFICE.

EDGAR L. HULL, OF WALTHAM, MASSACHUSETTS, ASSIGNOR TO WALTHAM WATCH COMPANY, OF WALTHAM, MASSACHUSETTS, A CORPORATION OF MASSACHUSETTS.

DESIGN FOR A TIMEPIECE-DIAL.

53,245.

Specification for Design.

Patented Apr. 29, 1919.

Application filed December 9, 1918. Serial No. 266,002. Term of patent 14 years.

To all whom it may concern:

Be it known that I, EDGAR L. HULL, a citizen of the United States, residing at Waltham, in the county of Middlesex and State of Massachusetts, have invented a new, original, and ornamental Design for a Timepiece-Dial, of which the following is a specification, reference being had to the accompanying drawing, forming part hereof.

The figure is a face view of a dial, showing my new design.

I claim:

The ornamental design for a timepiece dial, substantially as shown.

In testimony whereof I have affixed my signature.

EDGAR L. HULL.
